[57] ABSTRACT

A process for the production of high-purity urea-ammonium polyphosphate fertilizers from crystalline urea orthophosphate derived from the reaction of wet-process acid and urea. Initially, urea phosphate was pyrolyzed in one stage to give molten urea-ammonium polyphosphates that contained up to 95 percent of the phosphate as polyphosphate, dependent upon the reaction conditions used. Heat to effect condensation of

orthophosphate with urea to form polyphosphate was provided by steam. Reaction conditions ranging from a retention time of 1 minute at 350° F to 30 minutes at 260° F were satisfactory. The pyrolyzate contained mixtures of urea, ammonium orthophosphate, and ammonium polyphosphates and was dissolved in aqua ammonia to yield clear liquid fertilizers containing 12 to 15 percent nitrogen and 18 to 29 percent P₂O₅. Addition of either urea to the process to maintain a urea:biuret ratio of at least 16, or about 2 pounds NH₃ per unit P₂O₅, to the pyrolysis reactor prevented biuret precipitation in the liquid fertilizers. Granulation of urea-ammonium polyphosphate melt by conventional means gave solids containing 19 to 21 percent N and 45 to 47 percent P₂O₅. Supplementary, secondary, or micronutrient-containing materials may be incorporated in the liquid or solid products.
